UNITED STATES PATENT OFFICE.

LOUIS CLÉMENCET, OF WEST HOBOKEN, NEW JERSEY, ASSIGNOR TO GEORGE K. BIRGE, OF BUFFALO, NEW YORK.

DESIGN FOR WALL-PAPER.

SPECIFICATION forming part of Design No. 24,899, dated November 12, 1895.

Application filed October 15, 1895. Serial No. 565,804. Term of patent 3½ years.

To all whom it may concern:

Be it known that I, LOUIS CLÉMENCET, a citizen of the United States, residing at West Hoboken, in the county of Hudson, in the State of New Jersey, have invented and produced a new and original Design for Wall-Paper, of which the following is a specification, reference being had to the accompanying drawing, showing a part thereof.

○ The design consists of sprays or branches of flowers and leaves of the hydrangea arranged over the surface of the paper, as represented in the accompanying drawing.

The border of the design is formed of large vase-like ornaments filled with branches of the same flowers and leaves of the hydrangea, with connected ornamental scrolls at the base of the vase-like ornaments forming small panels, which are filled with small filigree-work, as shown in the drawing. 20

What I claim is—

The design for wall paper herein shown and described.

Witness my hand this 4th day of October, 1895.

LOUIS CLÉMENCET.
